[57] **CLAIM**

The ornamental design for a storage and display package, as shown and described.

DESCRIPTION

FIG. 1 is a perspective view from above, showing the design in a partially open configuration;

FIG. 2 is a front view of FIG. 1 in a closed configuration, the rear view being a mirror image;

FIG. 3 is a front view of FIG. 1 in a wholly open configuration;

FIG. 4 is a front view similar to FIG. 3 without the discs; and,

FIG. 5 is an enlarged side view of FIG. 4, the opposite side being a mirror image.

The broken line showing of discs is for illustrative purposes only and forms no part of the claimed design.
